UNITED STATES PATENT OFFICE.

ERICH J. PATELSKI, OF CHICAGO, ILLINOIS.

DISHWASHING APPARATUS.

Application filed December 17, 1928. Serial No. 681,181.

This invention relates to improvements in dishwashing apparatus, and more particularly to a novel adaptation of a power driven water circulating device to a sink, in which 5 the bowl serves as the dish receptacle during the washing operation.

Among the objects of the invention, is to provide an efficient and practical power driven agitating unit adapted to circulate 10 the body of the cleansing water in a manner to effectively and thoroughly cleanse the dishes.

A further object of the invention is to provide a sink equipped with a water circulating apparatus so arranged and designed as to be entirely separate from the bowl, thus permitting the sink to be available at all times, for uses other than the washing of dishes.

A further object of the invention is to provide a drying compartment as a part of the sink together with means for circulating the air through the drying compartment by a positively driven fan forming a part of the water agitating mechanism.

A preferred embodiment of the invention is clearly shown in the accompanying drawings, in which,

Figure 1 is a view in vertical section through a sink especially designed for the purpose and equipped with the water agitating and dish drying means.

Figure 2 is a top plan view of one end portion of the sink in which the bowl is located and showing the water agitating apparatus in horizontal section, and

Figure 3 is a view in vertical section taken on line 3—3 of Figure 1.

The sink herein disclosed is preferably of the cast metal and enamel form used extensively for kitchen equipment, and except for certain departures in design, made necessary by the incorporation of the dish-washing apparatus, it includes the usual drain board 1, a rear panel 2 extending vertically above the drain board, and a bowl 3, with the usual openings 4—4 in the rear panel and above the bowl through which the faucet connections extend. The sink is supported upon the floor and against the wall of the kitchen 50 by means of legs or brackets, whichever is the more convenient.

For reasons hereinafter appearing, the bowl 3 is fairly deep and preferably oval in shape, but otherwise similar in all respects to that of the ordinary sink. It has in its bottom wall, a drain 5, communicating with

the usual trap and drain connections 6, and having a perforated plate 7, set in flush with the bottom of the bowl.

For obvious reasons the bottom drain is 60 provided with a valve 8, so that the bowl can be filled with water during the washing operation. In addition, an overflow outlet 9 is preferably provided near the upper edge of the bowl and in its rear wall, said overflow 65 outlet being also provided with a valve 10 and connected with pipe connections 11 which lead to a common discharge. The valves of the bottom and overflow drains are preferably operated by means of a single handle 12 70 located near one end of the sink, said handle being connected with the valves by suitable operating members, so arranged that when the valve 8 in the bottom drain is closed, the valve in the overflow drain will be open, and 75 vice versa, thereby insuring the proper relative positions of the valves at all times. By the use of an overflow, the danger of the bowl overflowing during the dishwashing operation is avoided and maintains a uniform high water level which allows fresh 80 water to flow into the bowl during the washing operation, and the grease and particles of food floating on the top of the water to be carried off.

The agitating mechanism is mounted beneath the drain board 1, and comprises a motor 13 suspended from the underside of the drain board, by means of an inverted base plate 14, a cylindrical casing or chamber 90 15, opening into the bowl 3, near its bottom, and a circulating member 16 mounted within said casing and fixed to a shaft 17 journaled in a suitable bearing 18 at the outer or closed end of the casing and driven by the motor. 95 Intermediate the shaft bearing of the casing 15 and the motor is mounted a fan 19 to be used for the circulation of air for the purposes hereinafter to be set forth.

Referring more in detail to the rotative 100 water circulating member 16, the same comprises a cylindric hollow shell 20, somewhat less in diameter than the surrounding housing 15, and extending substantially the full length thereof. Cast integral with the outer 105 surface of the shell is a series of helical blades 21, three in number, arranged symmetrically about the shell and extending substantially the full length of the shell from a point short of its forward end and 110 projecting beyond its rear end into a space adjacent the closed end of the casing, which

is slightly rounded or spherical in contour. On the inside of the shell is a somewhat similar arrangement of blades 22 cast integral with the shell and an axial sleeve or bushing 23, which has fixed connection with the end of the drive shaft 17.

The internal blades 22 are two in number and likewise helical, but their pitch or lead is the reverse of that of the external blades 21, thus if it be assumed that the shell is rotated in a body of water, one set of blades will move the water one direction and the other set in the opposite direction. As will presently appear, this is the intended action of the blades, namely, that the internal blades drive the water inwardly through the shell to the rear of the housing 15, and thence carried forwardly again by the external blades 21, and discharged from the casing. This constant influx and discharge of the body of water from the bowl 3 promotes the circulation of water among the dishes which effects the cleaning action.

As already pointed out, the housing 15 fits within an opening in the bowl, preferably by means of a threaded flange and shoulder connection so that the parts can be readily disassembled. The entrance opening to the casing is covered by perforated plate or cap 24 which prevents solid matter from being carried into the casing and otherwise divides the casing and the bowl. The plate 24 is provided with an annular flange 24^a which fits within the opening to the casing and has screw threaded connection with the open end thereof. Moreover, the plate acts as a bearing for the shaft of the cylindric rotor, there being supported at the center of the plate an oilless bearing 25. The face of the plate 25 is substantially flush with the side wall of the bowl, although the bowl is preferably provided with depressions or recesses 3^a, 3^b on either side of the plate which expose portions of its annular flange 24^a.

A definite arrangement of apertures or slots are formed in the plate 24. As clearly shown in Figures 2 and 3, there are three groups of concentric slots in the circular face of the plate, the innermost and intermediate groups 26 and 27 being in alignment with the internal passage of the shell 20, whereas the outermost group 28 is in alignment with the annular space, surrounding the shell. Between the outer and the intermediate groups of openings 28 and 27, is an annular dividing wall or ring 29, of the same diameter as the cylindric shell of the rotor 20, the forward edge of the latter being in close proximity thereto with but a slight clearance between. In addition to the openings in the front face of the plate there are also two series of lateral openings 30, 30 in the annular flange 24^a of the plate, these openings facing radially toward the depressions 3^c, 3^d in the bowl. The lateral

groups of openings 30 serve the same purpose as the outer concentric group 28, since they also communicate with the space surrounding the rotor 16.

The action of the agitating mechanism and the manner in which the cleaning action is accomplished will be understood from the following: The bowl is first filled with a quantity of soapy water, the bottom drain being closed and in which position the overflow drain is open. The motor is then started and drives the rotor in a counter-clockwise direction so that the internal blades 22 function to draw the water into the housing through the registering groups of openings 26 and 27. Reaching the rear of the housing the water is picked up by the external blades 21 and carried forwardly along the outer passage and discharged into the bowl, the current being divided between the outer annular group of openings 29 and the lateral groups 30, 30. Due to the oval shape of the bowl and the curved depressions 3^c, 3^d the water thus discharged into the bowl, sets up a series of cross currents and eddies throughout the entire volume of water. Manifestly, it is impossible to accurately trace the various currents that would be set up, but some idea can be had of the thorough agitation that is produced, from the fact that the streams issue from both sides of the plate in a radial direction as well as longitudinally through the outer circular row of openings, so that there is a multitude of conflicting currents which produce the desired action for effective cleansing. The oval shape of the bowl further assists in promoting effective agitation in that it prevents any tendency toward a concerted movement about the center of the bowl, as would be present if it were circular, thus breaking up any general movement of the water into many small whirlpools or eddies.

Provision is also made for rapid drying of the dishes, and while the drying means may or may not form a part of the washing apparatus it forms a convenient addition thereto and makes a complete apparatus for dish-washing.

The drying of the dishes is made possible by the provision of a housing 31, which not only encloses the motor and other parts of the agitating mechanism, but provides a space therebelow in which the dishes may be placed after washing, a wire basket being ordinarily used for handling the dishes, both in washing and drying.

The housing 31 is constructed more or less like an oven, with side and bottom walls, and which depends from the under side of the drain board and below the sink apron 32, and the bowl 3. As already suggested, the upper part of the housing encloses the moving parts and the lower part forming

the drying space with horizontal partition wall 33 divides the two spaces. In this wall 33 near its end opposite the motor 13 is a series of transverse louvers 34 with openings leading to the space below. These louvers incline toward the fan 19, for directing the air currents created thereby into the drying space. A baffle 35 is also located in the upper space which extends from a point above the fan downwardly and toward the far corner of the space above the partition wall 33. Holes or other forms of openings 36 and 37, are located at suitable places in the housing walls or above and below the partition wall 33, so as to provide for the necessary circulation of air, which is kept in motion by the fan 19. A heating coil 38 may be conveniently placed in the bottom of the drying space for facilitating the drying operation. Access to the drying space, as well as to the mechanism above is had by means of a door 39, in the front wall of the housing. This door is hinged along its bottom (or side if preferred), and otherwise is similar to the ordinary oven door.

The apparatus thus disclosed provides a compact and unitary sink equipment for household use, having the advantage of combining in a single fixture all of the requirements for mechanical dish-washing and without interfering with its use for purposes for which the ordinary sink may be used. The agitating mechanism is completely removed from the sink bowl, thus leaving the latter free and open at all times, so that it can be kept clean, as well as usable for any purpose other than washing dishes. In short, the use of an apparatus embodying the present invention makes it possible to incorporate a mechanical dishwashing apparatus in a sink without any of the objectionable features that are present in other devices for this purpose.

I claim as my invention:

1. In an apparatus of the character described, the combination of an open receptacle, a cylindric casing communicating at one end with said receptacle and closed at its opposite end, a rotor mounted in said casing and comprising an open ended cylindric shell of reduced diameter arranged axially of said casing and dividing the space therein into internal and external passages connected at the closed end thereof, said shell having helical impeller blades extending lengthwise the outer surfaces thereof and radially of said external passage.

2. In an apparatus of the character described, the combination of a receptacle, a cylindric casing communicating at one end with said receptacle and closed at its opposite end, a rotor in said casing comprising an open ended cylindric shell of less diameter than said casing and extending axially thereof to form internal and external pas-

sages connected at the closed end of said casing, said shell having helical impeller blades of opposite lead extending lengthwise of the inner and outer faces thereof and radially of said passages.

3. In an apparatus of the character described, the combination of a receptacle, a cylindric casing communicating at one end with said receptacle and closed at its opposite end, a rotary impeller extending axially of said casing and comprising an open ended cylindric shell extending from the open end to a point adjacent its closed end, said shell being spaced radially inward from said casing to form an internal passage and an annular external passage connected beyond the inner end of said shell, and series of helical impeller blades of opposite lead extending longitudinally of the inner and outer surfaces of said shell and radially of said passages.

4. In an apparatus of the character described, the combination of a receptacle, a cylindric casing communicating at one end with said receptacle and closed at its opposite end, a rotor comprising an open ended cylindric shell extending axially of said casing and forming internal and external passages connected by a space at the closed end of said casing, and helical impeller blades of opposite lead extending along the outer and inner surfaces of said shell and radially of said passages, one of said blades projecting into said space at the closed end of said casing, whereby the water in said receptacle is drawn into said casing through one of said passages and discharged therefrom through the other passage.

5. In an apparatus of the character described, the combination of a receptacle, a cylindric casing communicating at one end with said receptacle and closed at its opposite end, a rotor comprising an open ended cylindric shell arranged axially of said casing and forming within said casing external and internal passages communicating with said receptacle at the open end of said casing and connected with each other at the closed end of said casing, said shell having series of helical impeller blades of opposite lead extending lengthwise of its inner and outer surfaces and radially of said passages, one of said series of blades extending beyond the inner end of said shell into the space at the closed end of said casing.

6. In an apparatus of the character described, the combination of a receptacle, a cylindric casing communicating at one end with said receptacle and closed at its opposite end, a rotor comprising an open ended cylindric shell arranged axially of said casing and reduced in diameter to form external and internal passages communicating with said receptacle at the open end of said casing and terminating short of the

closed end of said casing to provide connecting passage, series of helical impeller blades of opposite leads extending lengthwise of the inner and outer surfaces of said shell 5 and radially of said passages, and a plate fitting over the opening to said casing and having openings therein registering with said external and internal passages.

7. In a dish washing apparatus, the combination of a bowl, a horizontal cylindric casing opening at one end into said bowl adjacent its bottom and closed at its opposite end, a shaft extending axially of said casing and through the end wall thereof, 10 a motor operatively connected with said shaft exterior said casing, a cylindric shell open at both ends and mounted on said shaft within said casing, said shell being spaced radially from the inner wall of said casing 15 to form an annular space therebetween, and inwardly from the closed end of said casing to provide a space connecting said annular space with the internal space of said shell, said shell having a series of internal and 20 external impeller blades of opposed lead extending radially of said spaces, the ends of one series of blades extending beyond said shell into the space at the closed end of 25 said casing.

8. In a dish washing apparatus, the com-

bination of a bowl, a horizontal cylindric casing opening at one end into said bowl adjacent its bottom and having a concave end wall at its opposite end, a shaft extending axially of said casing and through the end wall thereof, 35 a motor operatively connected with said shaft exterior of said casing, a cylindric shell open at both ends and mounted on said shaft within said casing, said shell being spaced radially from the inner wall of said casing to form an annular passage therebetween and terminating short of the closed end of said casing to provide a space connecting said annular passage with the internal passage of 40 said shell, series of helical impeller blades of opposed lead extending longitudinally of the inner and outer surfaces of said shell and radially of the internal and external passages, said outer series of blades 45 extending beyond the inner end of said shell into said space beyond, and a plate fitting into the open end of said casing and provided with openings registering with said passages. 50

In witness whereof, I hereunto subscribe my name this 4th day of December, A. D., 1923.

ERICH J. PATELSKI.
